Reading, Pa., a corporation of Delaware

Application February 12, 1949, Serial No. 76,134

9 Claims. (Cl. 26—11)

1

The present invention relates generally to yarn cutting apparatus and more particularly to apparatus for cutting and removing the floats of patterning wrap yarns extending between successive knitted rib tops joined together in string-work form.

In the knitting of rib tops on a circular rib knitting machine, the successive tops are delivered by the machine in the form of stringwork in which the tops are joined together by special removable separating courses of knitting between adjacent tops by means of which the tops may be individually separated from each other. However in the case of a circular rib wrap yarn decorated knitting machine, the wrap threads knitted into and forming the pattern in each of the successive tops extend as floats between the inside of the tubular tops after the separating courses have been removed. Consequently the wrap yarn floats must be removed before the tops can be completely separated and it is desirable that the floats be severed adjacent to the points at which they are knitted into the fabric of adjacent tops as not to leave objectionable extending lengths of the wrap yarns. It will be obvious that the length of the wrap yarn floats will vary with the length of each series of tops and with the particular pattern formed by the wrap yarn in the fabric of the tops.

It is accordingly a principal object of the present invention to provide an apparatus which will quickly and automatically remove the wrap yarn floats between successive wrap yarn decorated rib tops.

It is a further object of the present invention to provide an apparatus which is readily adjustable for different lengths of wrap yarn floats so that regardless of their length, the floats may be severed adjacent to the points at which the wrap yarns are knitted into the fabric.

With the above and other objects in view as will be apparent from the following description of the invention, a preferred form of which is illustrated in the accompanying drawings in which:

Figure 1 is a view of a pair of tubular rib tops joined together by the wrap yarn patterning floats.

Figure 2 is a plan view of the apparatus of the present invention.

Figure 3 is a front view in elevation of the apparatus shown in Figure 2.

Figure 4 is a side view of the apparatus shown in Figure 3 taken on line 4—4 of Figure 3 and showing the drive belt and pulley in phantom lines.

2

Figure 5 is a perspective view of a detail of the invention showing the lever operating means.

Figure 6 is a sectional view on line 6—6 of Figure 4.

Figure 7 is a sectional view on line 7—7 of Figure 4.

Figure 8 is an enlarged view of the clutch and driving means shown in Figure 4.

Figure 9 is a view similar to Figure 8 with the clutch in engaged position.

Figure 10 is a perspective view showing the clutch operating means.

Figure 11 is a vertical sectional view through the cutter apparatus in fully opened position.

Figure 12 is a sectional view of the apparatus shown in Figure 11 taken on line 12—12.

Figure 13 is a view similar to Figure 11 with the cutter apparatus in an intermediate position, and

Figure 14 is a view similar to Figure 11 with the cutter apparatus in fully closed position.

Referring to the drawings it will be seen that the present invention provides a cutter device or apparatus indicated at 10 adapted to be operated when the rod 11 thereof is moved vertically by means of a lever 12 adapted to be power operated for one revolution of driven pulley 13 when handle 14 is momentarily depressed by the operator.

The power operating means is preferably located under a suitable table top 15 and includes a pair of bearings 16, 16 spaced from each other and from the table 15 by blocks 17 and 18, the bearings 16, 16 being secured in place by bolts 19, 19 extending through table 15 and blocks 17 and 18. The bearings 16, 16 support a normally idle shaft 20 upon which is mounted for free rotation thereon the pulley 13 driven by belt 21 from any suitable source of power. Also mounted on shaft

20 and secured to pulley 13 for rotation therewith is a toothed clutch wheel 22 by means of which the shaft 20 may be rotated at times with the pulley 13, usually for one revolution of the latter. An arm 23, secured to the shaft 20 alongside of clutch wheel 22 by any suitable means as by pin 24, extends beyond the wheel 22 where a pawl 25 is pivoted thereon at 26 to overlie the teeth of the wheel 22. One end 27 of pawl 25 is shaped

to engage the teeth of wheel 22 and is urged into engagement therewith by spring 28 secured to the end 27 of the pawl 25 and to the arm 23. It will be obvious, as seen in Figure 9, that when pawl 25 is permitted to engage wheel 22 that the shaft 20 will be caused to rotate with the driven pulley 13. To control the movement of pawl 25 a bolt member 29 movable in housing 30 is provided.

An arm 31 secured to table 15 by bolts 32, 32 supports housing 30 in position so that bolt 29 overlies the arm 23 where it controls the action of pawl 25. A pin 33 secured to bolt 29 extending outwardly through a slot 34 in face plate 35 of housing 30 serves as the means by which bolt 29 may be raised vertically against the action of compression spring 36 and also serves as a limit at the bottom of slot 34 for the downward movement of bolt 29 under action of spring 36. The spring 36 is compressed by any suitable means as by opening in table 15 between the upper face of bolt 29 and a plate 37 secured to the table top 15 by screws 38, 38. The lower face of bolt 29 is provided with means to stop the arm 23 and to hold pawl 25 away from wheel 22 when the bolt 29 is in lowered position of Figure 8. As best seen in Figure 10 the lower face of bolt 29 is provided with the spaced members 39 and 40 adapted to engage respectively with opposite end 41 of pawl 25 and with the projection 42 at the end of arm 23.

Assuming that the parts are as shown in Figure 8, it will be seen that with bolt 29 in lowered position the end 42 of arm 23 is in engagement with stop 40 and the end 41 of pawl 25 is in engagement with notch 43 thus keeping the pawl end 27 out of engagement with wheel 22. Accordingly shaft 20 and the parts thereon will be kept from rotation with the normally rotating pulley 13 and wheel 22. Should bolt 29 be momentarily raised, as by moving pin 33 upwardly, to release arm 23 and pawl 25, pawl end 27 will be drawn by spring 28 into engagement with clutch wheel 22 and stop member 40 will be withdrawn from engagement with the projecting end 42 of arm 23, thereby causing shaft 20 to be rotated by driven pulley 13. Now should bolt 29 be permitted to drop to its lowermost position before shaft 20 has completed a revolution, then as one revolution of shaft 20 and arm 23 is about to be completed, the power of spring 36 is sufficient so that inclined surface 44 of the lower face of bolt 29 will engage the end 41 of pawl 25, turning the latter about its pivot point 26 to withdraw pawl end 27 from engagement with wheel 22 against the action of relatively light spring 28. Upon withdrawal of the pawl end 27 from driving engagement with wheel 22, the pawl 25 comes to rest with the end 41 thereof in notch 43 of bolt 29 and at the same time bolt stop 40 engages projecting end 42 of arm 23 to hold the latter in idle position of Figure 8. Thus each time that bolt 29 is momentarily raised for a period of time less than that required for a revolution of pulley 13, the parts above described are actuated to rotate shaft 20 for a single revolution. A lever 45 pivoted on stud 46 is provided to raise the pin 33 of bolt 29 as required, the lever 45 having an arm 47 with end 48 offset under pin 33. The handle 14 comprising a circular member freely rotatable on a stud secured to the end of lever 45 provides a convenient means by which the operator may momentarily operate lever 45 to cause shaft 20 to rotate for a single revolution. The stud 46 is supported by a suitable bracket secured to the front of block 17.

The purpose of rotating shaft 20 for single revolutions is to raise and lower lever 12 about its pivot point on stud 50 so that the reduced end 51 which extends between rollers 52, 52 of yoke 53 forming an intermediate part of rod 11, will raise and lower rod 11 to actuate the cutter mechanism 10. The stud 50 is supported by a suitable bracket 54 secured to the underside of

table 15 by bolts 55. The shaft 20 which terminates just short of lever 12 has a collar 56 secured to its end so that a roller 57 projecting from the outer face of the collar fits into a slot 58 in lever 12. It will be noted that roller 57 is offset with relation to shaft 20 and consequently for each rotation of shaft 20, from its idle position of Figure 4, lever 12 will be lowered and raised to complete a cycle of operation. As shown in Figure 5, the roller 57 is shown in active position with the lever 12 lowered.

The wrap yarn float cutting mechanism 10 is provided with a housing comprising spaced parallel angle formed side walls 59, 59 secured to and extending upwardly from the top of a channel shaped base member 60 extending rearwardly beyond the side walls 59, 59 as at 61, the channel legs of the extension 51 being undercut at 62 to fit over the front edge of table 15 and be suitably secured thereto as by screws 63, 63. It will be obvious that the side walls and base of the housing may be integrally formed. Extending inwardly from the front edges of each of the side wall members 59, 59 adjacent the tops thereof are in-line like slotted openings 64, 64 tapered as at 65, 65, these openings being parallel to the base 61 and of sufficient length to receive all of the wrap yarn floats to be severed. The outer sides of the walls 59, 59 are tapered above and below the slots 64 as at 66, 66 to permit the yarn floats to be cut the desired length. Stationary knife blades 67, 67 are secured to the inner faces of walls 59, 59 below slots 64, 64 so that the upper cutting edges of the blades are substantially coincident with the lower edges of the slots. Movable knife blades 68, 68 having lower cutting edges adapted to cooperate with stationary blades 67, are supported for turning movement on studs 69, 69 fastened at their inner ends in arms 70, 70 of the movable knife blades. The outer headed ends of studs 69, 69 extend through bearing holes in the walls 59, 59 and are encircled by compression springs 71, 71 which serve to maintain the movable blades in yielding contact with the stationary blades for efficient cutting action. The movable blades are further maintained in yielding engagement with the stationary blades by means of a compression spring 72 extending between the movable blades and encircling separate in-line studs 73, 73 fixed at one end in the free ends of the movable blades 68, 68 and extending toward each other.

To operate the movable blades, a lever 74 is provided pivoted on a shaft 75 which is supported by and extends between the side walls 59, 59 at their forward ends above the slots 64. Spacing collars 76, 76 maintain the lever 74 centrally of the side walls 59, 59. A yoke 77 formed at the rear end of lever 74 extends around upright rod 11 and depending arms 78, 78 support a pin 79 which extends outwardly from both sides of the arms 78, 78 to overlie the movable knife blades 67, 67. A set screw held collar 80 on pin 79 between arms 78, 78 serves to secure the pin in position. The lever 74 is adapted to be moved from its uppermost position in Figure 11 to its lowermost position in Figure 14 by means of rod 11 as the latter is moved downwardly by the means previously described, an adjustable stop member 81 on the upper end of rod 11 normally spaced from the yoke 77, Figure 11, engages yoke 77 after traversing the spaced distance and thereafter depresses lever 74 to the position of Figure 14. Depression of lever 74 causes pin 79 to actuate movable blades 68, 68 to cross slotted open-

ings 64 and stationary blades 67, thereby severing any yarn floats present between the cutting blades. It is intended that the wrap yarn floats to be cut should be placed in the slots 64 extending between the walls 59 in position to be severed by the cutting blades. The lengths of the wrap yarn floats may vary with different rib tops as will be apparent from Figure 1 where two of a series of tubular tops 82, 82 are shown connected together by interiorly disposed wrap yarns 83 which have been knitted into the tops 82 to form the visible pattern blocks 84 and lines 85 in contrasting color upon the base fabric 86. The lower edge 87 of each top 82 is connected to the upper edge 88 of the adjacent top 82 by a removable separating course (not shown) as the tops come from a circular rib knitting machine as is well known in the art and in Figure 1 the tops 82 are shown as they are after the separating courses have been removed in the usual manner. It will be obvious that individual tops of varying lengths or of varying wrap yarn formed patterns will have varying float lengths of the wrap yarns between adjacent tops. Accordingly the cutter mechanism is provided with means adjustable for the different lengths of floats which will insure that the wrap yarn excess may be severed adjacent to the points in the fabric where the wrap yarns are first and last knitted to form the pattern. The yarns are severed so as to leave relatively short lengths extending from the back of the fabric sufficient so that the yarns will not pull out of the fabric. The operator spreads the tops apart and inserts the float yarns 83 joining adjacent tops 82 in the slots 64 with the upper and lower edges 88 and 87 of the tops on the outer sides of the side walls 59, the slots 64 being too narrow to permit the fabric of the tops to pass therethrough. The operator then momentarily depresses the handle 14 and the mechanism previously described is caused to be power operated to actuate the knife blades to sever the floats, thus completely separating the tops.

To take up the slack in the wrap yarn floats before being severed, there is provided an adjustable take-up plunger member 90 which is adapted to move from its position in Figure 11 above slots 64 to a position below slots 64 as shown in Figure 13, the distance below the slots 64 being adjustable and dependent upon the length of the yarn floats. The plunger 90 mounted centrally of walls 59 on upright rod 91 parallel to rod 11, is provided with notches 92 on its underside to engage floats 83. The rod 91 having a reduced threaded end portion 93 extending through an opening in plunger 90, is provided with a spring 94 and a nut 95 by means of which the plunger is held against the shoulder provided by the reduced end 93. Another opening 96 at the rear of plunger 90 is provided by means of which the rod 11 serves as a guide upon which the plunger may move vertically. The rods 11 and 91 are guided for vertical movement in sleeves 97, 98 suitably secured to the floor of base 61. The upper side of the plunger 90 is reduced at its forward end as at 103 to provide a flat surface which is adapted to engage spring covered pins 73, 73, Figure 14, of lowered movable cutters 68, 68 so that as plunger 90 is raised it will return the cutters 68 to their opened position of Figure 11. The base 61 is provided with opening 99 to permit the severed float ends to drop into any convenient receptacle. The lower end of rod 11 is threaded to receive the adjustable rounded nut 100 knurled on its outer surface and centrally

undercut at 101 to receive the arms of the supporting member 104. The supporting member 104, free to slide on rod 91 by means of a suitable opening, has secured to it by screw 103 a flat spring 102 curved to engage the knurled surface of nut 100 and thus hold the same in an adjusted position. A stop member 105 suitably secured to the lower end of rod 11 is adapted to raise arm 106 and rod 91, the arm 106 having a split end adapted to extend around the rod 11 overlying the stop 105. A set screw 107 is provided to adjustably secure the arm 106 in place on rod 91.

In the operation of the described apparatus, after the float threads 83 have been inserted in 15 and stretched across the slots 64, the operator momentarily manually depresses the handle 14 of lever 45. The movement of lever, by the means hereinabove set forth, causes shaft 20 to be revolved for a single revolution thereby causing 20 roller 57 to actuate lever 12 and impart a single reciprocation to rod 11. The first half of each reciprocation is a downward movement for rod 11 and during the initial part of this movement the rod 11 moves from its uppermost position 25 of Figure 11 to that shown in Figure 13 in which knob 81 is adjacent yoke 77. This is sufficient for the member 104 on rod 11 to move downwardly to engage the member 106 and move associated rod 91 downwardly so that take-up plunger 90 30 removes the slack in float threads 83 drawing adjacent successive tops 82 close to the outer sides of walls 59. The yielding connection provided by spring 94 insures that the threads will not be broken. In this position of the parts, further 35 movement of rod 11 downwardly will cause knob 81 to pivot arm 74 so that pin 79 will actuate blades 68 to move the same to the position of Figure 14 thereby severing the ends of the floats adjacent the points at which the wrap yarns are 40 knit into successive rib tops.

The second half of each reciprocation is an upward movement for rod 11 during which block 105 on rod 11 engages the underside of member 106 to raise rod 91 and the plunger take-up 90. 45 The continued upward movement of the rods 11 and 91 causes the upper surface 108 of take-up 90 to engage spring encircled pins 73 to re-set the movable blades 68 and arm 74 to the position of Figure 11, preparatory to the insertion of other 50 float threads in slots 64. It will be obvious that for different lengths of float threads the adjustable nut 100 may be accordingly moved up or down on the rod 11 so that amount of slack removed from the float threads by take-up 90 will 55 vary as required by the varying lengths of the floats to be severed. The apparatus provides means which is manually operable at a rapid rate for removal of float threads between tops being limited only by the skill of the operator in 60 inserting the float threads in the slots to be severed.

We claim:

1. An apparatus for removing the interior wrap yarn floats extending between spaced pattern areas of successive tubular wrap patterned stringwork formed rib tops comprising a pair of spaced cutting members adapted to receive the floats between separated adjacent tops but not the tops themselves, the float lengths between 65 said areas being substantially greater than the distance between said members, means to position the pattern areas adjacent said members and means to operate said members to sever said floats adjacent to the points at which said yarns 70 are knitted into successive tops.

2. An apparatus for removing the interior wrap yarn floats extending between spaced pattern areas of successive tubular wrap patterned stringwork formed rib tops comprising a pair of spaced cutting members adapted to receive the floats between separated adjacent tops but not the tops themselves, the float lengths between said areas being substantially greater than the distance between said members, means to elongate said floats and position their end portions adjacent said members and means to operate said members to sever said floats adjacent to the points at which said yarns are knitted into successive tops.

3. An apparatus for removing the interior wrap yarn floats extending between spaced pattern areas of successive tubular wrap patterned stringwork formed rib tops comprising a pair of spaced cutting members adapted to receive and to sever the said floats between adjacent separated tops, the lengths of said floats to be severed being greater than the distance between said members, guard means to prevent said tops from entering said members, and a yarn take-up between said members adapted to remove the slack in said float yarns and to position the pattern areas of said tops adjacent said members.

4. An apparatus for removing the interior wrap yarn floats extending between spaced pattern areas of successive tubular wrap patterned stringwork formed rib tops comprising spaced wall members provided with parallel open end slots adapted to receive the floats between separated adjacent tops but not the tops themselves, stationary knife blades disposed on the inner sides of said members having upper cutting edges substantially coincident with said slots, movable knife blades normally spaced from and adapted to be moved toward said stationary knife blades to cooperate therewith to sever said floats, a yarn take-up between said wall members normally positioned above and adapted to be moved to a position below said slots to remove the slack in said float yarns thereby positioning the pattern areas of said tops adjacent said blades and means to operate said take-up and said blades in timed relation to sever said floats.

5. An apparatus as set forth in claim 4 in which said take-up and blade operating means comprises a vertically movable rod operatively related to said take-up and to said blades, said rod being adapted to be operated for single reciprocations, and during the first half of its reciprocation operating first the yarn take-up and then the blades and during the second half of its reciprocation re-setting said yarn take-up and said blades.

6. An apparatus for removing the interior wrap yarn floats extending between spaced pattern areas of successive tubular wrap patterned stringwork formed rib tops comprising spaced wall members provided with parallel open end slots adapted to receive the floats between separated adjacent tops but not the tops themselves, cutters disposed on the inner sides of said members operatively related to said slots to sever said floats, a yarn take-up between said wall members normally positioned above and adapted to move to a position below said slots to remove the slack in said float yarns thereby positioning the pattern areas of said tops adjacent said blades, a vertically movable rod adapted when moved for a single lengthwise reciprocation to operate said take-up and said blades in timed relation to sever said floats and to re-set said take-up and said

blades, a power driven rotary shaft, a handle control and means operative upon momentary manual movement of said handle control to cause said rod to be operated by said shaft for a single revolution thereof.

7. A float thread severing apparatus comprising spaced wall members provided with parallel open end slots adapted to receive the floats, the length of said floats being substantially greater than the distance between said members, cutters disposed on said members operatively related to said slots to sever said floats, a yarn take-up between said wall members normally positioned above and adapted to move to a position below said slots to remove the slack in said float threads thereby positioning the end portions of said floats adjacent said cutters, a vertically movable rod operatively related to said cutters, a second vertically movable rod operatively related to said yarn take-up and to said first named rod, means for imparting single reciprocations to said first named rod, and a lost motion connection between said cutters and said first named rod whereby initial movement of the latter during the first half of the reciprocation operates only said second named rod and said yarn take-up and further movement operates said cutters, the first named rod during the second half of the reciprocation operating said second named rod to re-set said take-up and said cutters.

8. A float thread severing apparatus as set forth in claim 7 in which means are provided operatively related to said vertically movable rods whereby the extent of the yarn take-up travel prior to the operation of the cutters may be regulated.

9. A float thread severing apparatus comprising spaced wall members provided with parallel open end slots adapted to receive the floats, the length of said floats being substantially greater than the distance between said members, cutters disposed on said members operatively related to said slots to sever said floats, said cutters comprising stationary blades with upper cutting edges substantially coincident with said slots and movable pivotally mounted blades normally spaced above said slots adapted to be moved to a closed position alongside said stationary blades, pins on the free ends of said movable blades extending toward each other, a compression spring encircling each of said pins, a cutter operating arm pivotally mounted at one end on said wall members above the entrance end of said slots and having a yoke at its other end, a yarn take-up between said wall members normally positioned above and adapted to move to and return from a position below said slots where it removes the slack in said float threads thereby positioning the end portions of said floats adjacent said cutters, said take-up on its return movement being adapted to engage said spring encircled pins of the movable blades in closed position to re-set them in opened position, a vertically movable rod having one end extending upwardly between the yoke on said cutter operating arm, a knob on said end of the rod spaced from said yoke adapted to engage the latter as the rod descends, a second vertically movable rod operatively supporting said take-up adapted to lower and raise the latter, a spring interposed between said second named rod and said take-up to provide a yielding connection therebetween in the downward take-up movement, adjustable means on the lower ends of said rods operatively related whereby upon downward movement of said first

named rod the extent of travel of said second named rod and the downward movement of said take-up prior to actuation of said movable blades may be regulated, and means for imparting manually controlled single reciprocations to said first named rod, the first half of each reciprocation lowering said first named rod to actuate said second named rod, take-up and cutters while the second half of each reciprocation raises said first named rod to re-set said second named rod, take-up and cutters.
